ICE CARRIER

Wilbur F. Crawford, Waco, Tex.

Application April 10, 1934, Serial No. 719,935

13 Claims. (Cl. 224—45)

This invention relates to carriers especially adapted for use in the delivery of ice.

Ice carriers are known to be subject to hard usage and it has been a difficult problem to provide a carrier capable of resisting the strain of being repeatedly dragged, after a manner of speaking, with its substantial load of ice, from an ice delivery truck and lifted to the back of the delivery man who, upon reaching the box or other place of delivery of the ice, lowers the carrier to the floor with little or no thought of the fact that rough handling of the carrier causes rapid wear thereon, particularly at the corners of the carrier and that abuse of the carrier in various ways is conducive to tears and leaks which impair and soon destroy the usefulness of the carrier for its intended purpose.

Various means have been tried in an effort to reinforce the carrier at the corners where the bag is subject to the greatest wear and strain. For example, three-sided leather corner pieces have been employed but none has produced the desired results because after a short period of use and repeated wetting the same become hardened and are easily torn off. Also, three-sided leather corner pieces, of necessity, have troublesome folds and have failed to respond to the strong need for an ice carrier that is resistant to wear to a high degree and one which will remain waterproof under the use and abuse to which ice carriers are caused to undergo.

In cases where metal corner pieces have been applied by riveting or stapling as suggested by the prior art, the rivets or staples, as the case may be, have been found to work larger holes in the fabric forming the body of the ice carrier and thus render the carrier leaky and susceptible to destructive tearing, especially under repeated and heavy loads of ice and other strains.

With an appreciation of the foregoing and other disadvantages accompanying the use of metal corner pieces, the invention forming the subject of this application contemplates an ice carrier having rigid corner pieces applied to the carrier in a manner which protects the adjacent fabric against leaks and tears and which resists wear and abuse to a point where the life of the carrier is substantially increased without a corresponding increase in the cost of manufacture.

Other objects and advantages will be apparent during the course of the following description.

In the accompanying drawings, forming a part of this application, and in which like numerals are employed to designate like parts throughout the same, of the several views of the invention,

Figure 1 is a fragmentary perspective of an ice carrier embodied in the invention, parts being broken away for the purpose of additional illustration.

Figure 2 is a vertical detail sectional view taken on line 2—2 of Figure 1.

Figure 3 is a fragmentary group perspective view of the carrier shown in Figure 1, parts being shown in section.

Figure 4 is a fragmentary plan view of a boot embodied in the invention.

Figure 5 is a fragmentary perspective disclosing a slight modification of the invention.

Figure 6 is a vertical detail sectional view taken on line 6—6 of Figure 5.

Figure 7 is a detail horizontal sectional view taken on line 7—7 of Figure 6.

Figure 8 is a fragmentary group perspective illustrating another form of carrier, parts being in section.

Figure 9 is a detail vertical sectional view through the form of carrier shown in Figure 8.

In the drawings, the numeral 10 generally designates an ice carrier in which the bottom, side and end walls are formed from a single piece of waterproof canvas or other suitable fabric and since the carrier is formed principally from a single piece of material, there is avoided the possibility of leaks at seams. The side walls 14 are extended substantial distances above the end walls 16 and are provided with suitable handles by which the carrier may be mounted on the back of the delivery man or suspended from the hand.

The single piece of waterproof fabric constituting the body of the carrier is provided at predetermined points with inwardly directed triangular double folds 12 defining side walls 14, end walls 16 and a rectangular bottom 18, such folds 12 being secured to the inner surfaces of the end walls 16 by rows of stitching. With the triangular folds 12 thus stitched in place, the bag or carrier is given its intended form and there is an absence of seams through which water may leak, it being observed in this connection that the drippings from the ice collect in the rather shallow base portion of the carrier and if the bag is to serve to maximum advantage, it is necessary that such drippings be prevented from leaking either onto the clothing of the delivery man or onto the floor of the house into which the ice is delivered.

It will be seen from Figure 3, that in addition to giving the bag its intended form, the double triangular folds 12 in being securely stitched to

the end walls 16 actually strengthen and reinforce the carrier adjacent the corners thereof.

By reference to Figures 1 and 3, it will be seen that a reinforcing waterproofed fabric 22 underlies the bottom 18 and has the corners thereof provided with double triangular folds fitting between the inner and outer layers of the double folds 12 and stitched in place by the same stitching which secures in place the folds 12 so that the marginal portions of the reinforcing fabric covering 22 are caused to closely embrace the sides and ends 14 and 16, respectively. In fact, the edge portions of the reinforcing member or covering 22 are stitched to the adjacent portions of the side and end walls 14 and 16, respectively, making the covering a permanent and integral part of the carrier, protecting the base portion of the carrier against tearing and leakage.

As an important and additional strengthening medium for the base or lower portion of the carrier, there is provided a boot 26 formed from a single piece of waterproof fabric having a bottom wall underlying the carrier proper and having side and end walls 28 and 30, respectively, extending along the lower portions of the side and end walls 14 and 16, respectively, of the carrier.

By reference to Figure 4, it will be seen that the single piece of fabric from which the boot is formed is provided at the corners thereof with incisions defining partly severed portions 34 folded in against the side walls 28 and initially secured in position by stitching or other suitable means.

Referring now to one of the principal features of the invention, it is pointed out that inner and outer triangular rigid metallic corner pieces or braces 40 and 42, respectively, are located at the corners of the boot and are secured to the side and end walls 28 and 30, respectively, of the boot through the medium of appropriate fastening elements, such as rivets 44, these rivets being extended through the corner pieces and the intervening portions of the walls 28 and 30 and the folds 34 so as to clamp the same flatly and firmly in place and thus afford protection against leakage and the possibility of tearing.

That is to say, when the rivets 44 are extended through the corner pieces 40 and 42 and the intervening fabric, and headed under pressure, the corner pieces will distribute the binding strain of the rivets over rather wide areas. For this reason, the holes necessarily formed as a result of the application of the rivets do not tend to enlarge as a result of strain on the carrier and thus there is avoided the possibility of tearing or leakage at the corners of the boot.

To put this matter in another light, the portions of fabric contiguous to the rivets 44 are firmly and uniformly clamped over generous areas by the inner and outer corner pieces 40 and 42 respectively, to avoid the enlargement of the holes due to the presence of the rivets and to prevent tearing of the adjacent fabric. It is important to observe that, although the boot is permanently united with the carrier itself by the marginal stitching shown in Figures 1 and 2, the rivets 44 do not extend through the fabric forming the side and end walls of the carrier and thus are not in any sense conducive to leaks or ripping of the material forming the carrier.

In addition, as previously stated, the manner of application of the rivets to the boot protects the fabric of the boot from tearing and leakage.

Thus, the employment of the metal corner pieces

40 and 42 greatly increases the wear resisting properties of the carrier, without at the same time rendering the carrier susceptible to those leaks and tears which would interfere with its usefulness.

In summarizing the subject matter of Figures 1 to 4, it will be seen that the same embodies an ice carrier formed principally from a single piece of waterproof fabric and having permanently connected thereto a boot in which the corners thereof are provided with inner and outer rigid metallic three-sided corner wear-resisting elements applied by rivets in a manner which clamps the immediately adjacent fabric of the boot firmly and uniformly between the corner pieces and thus protects the boot fabric against leaking and tearing, such rivets being exteriorly of the carrier, thus avoiding penetration by those rivets of the single piece of fabric forming the principal part of the carrier. This gives multiple protection against leakage and rapid wear on the body of the carrier, in addition to which there is to be considered the fact that the permanent attachment of the boot to the carrier and the employment of the intervening protecting fabric 22 gives to the carrier a strength and stiffness by which the carrier is enabled to withstand hard usage.

In the form of invention illustrated in Figures 5, 6, and 7 the carrier is generally designated by the numeral 50 and is formed from a single piece of waterproof fabric folded in at predetermined points as indicated at 54, after the fashion of the folds 12, to define side and end walls 52 and 53, respectively, such walls cooperating in the formation of a shallow container for the reception of ice and for the collection of drippings from the ice, while the side walls 52 are continued substantial distances above the end walls and are provided with suitable handles by which the carrier may be mounted upon the back of an ice delivery man or suspended from the hand of the delivery man.

In the form of invention shown in Figures 5, 6 and 7 the carrier is provided exteriorly of the base portion thereof with a reinforcing or strengthening fabric 56 folded at the corners thereof to produce triangular folds 58 located between the inner and outer layers of the triangular folds 54 of the carrier itself and such folds 54 and 58 are initially secured by stitching or other suitable means to the side and end walls 52 and 53, respectively, of the carrier and to the side and end walls of the reinforcing member 56 giving to the carrier its intended form and at the same time strengthening and reinforcing the same.

It is clearly shown in Figures 5, 6 and 7 that the base corners of the carrier are provided with inner and outer three sided corner pieces 60 and 62, respectively, secured in place by suitable fastening elements, such as rivets 64 which penetrate the intervening fabric and clamp the corner pieces firmly in place against broad areas of fabric to afford a high degree of protection, first against the enlargement of the holes due to the presence of the rivets, and second, against tearing of the adjacent fabric, it being observed in this latter connection, that the corners of the carrier have been found to be subjected to a substantial portion of the strain and it is at these points that the carrier so often leaks and tears.

In other words, the manner of application of the corner pieces 60 and 62 to the carrier does not, in any manner, interfere with the leak-resisting ability of the carrier due to the forma-

tion of the same principally from a single piece of waterproof fabric.

Where inner and outer cooperating corner pieces are employed the same are similarly dimensioned, so that when finally in place, the inner corner piece will be somewhat higher or out of exact line with the outer corner piece. It has been found that this avoids cutting or weakening of the bordering fabric as a result of repeated bending in the region of the corner pieces.

In the structure shown in Figures 8 and 9, the body of the carrier is formed from a single piece of waterproof fabric having the base corner portions thereof provided with inwardly directed triangular folds 70 stitched or otherwise secured to the end walls 72, so as to assist in maintaining such end walls substantially at right angles to the side walls 74 and thus aid in shaping the carrier.

The carrier in Figures 8 and 9 is shown to be provided with external three-sided corner plates 76 secured in position by rivets 78 penetrating the end and side walls 72 and 74 respectively and the folds 70. The inner ends of the rivets 78 have broad inner ends distributing the pressure of the rivets over wide areas and thus protecting the intervening fabric against tearing or leaking.

In Figures 8 and 9, it is clearly illustrated that the carrier may be provided with an outer protective covering 80, corresponding to the protecting covering shown in Figure 1 and penetrated by the rivets 78, or other appropriate fastening elements.

With reference to the foregoing description taken in connection with the accompanying drawings, it will be apparent that an ice carrier constructed in accordance with this invention has vastly improved wear-resisting qualities and that the manner of application of the corner pieces looks to the provision of a carrier in which the corners thereof are not susceptible to leakage or tearing and in which the cost of manufacture is not materially increased.

Also, the foregoing illustrates that the invention forming the subject of this application is capable of a variety of mechanical expressions and that such changes in arrangement and construction of parts may be made as will remain within the spirit of the invention and the scope of what is claimed.

Having thus described the invention what is claimed is:

1. In an ice carrier, a body formed from a single piece of waterproof fabric having side and end walls and a bottom, a boot receiving said bottom and the adjacent portions of the side and end walls and having side and end walls permanently secured to the side and end walls of the fabric forming said body, and inner and outer corner pieces secured to the side and end walls of the boot interiorly and exteriorly thereof and exteriorly of the waterproof fabric body of the carrier.

2. In a carrier for ice, a body formed principally of a single piece of waterproof fabric, a boot receiving a portion of the body of the carrier and having side and end walls and a bottom, and inner and outer three-sided cornered pieces located at the corners of the boot exteriorly of the waterproof fabric of the body of the carrier.

3. In a carrier for ice, a body formed principally of flexible waterproof fabric, a boot receiv-

ing a portion of the fabric body of the carrier and having side and end walls and a bottom, rigid inner and outer three-sided corner pieces located at the corners of the boot exteriorly of the said waterproof fabric of the body of the carrier, and fastening elements passing through the said inner and outer corner pieces and clamping the inner and outer corner pieces flatly against the intervening portions of the boot to protect such intervening portions of the boot against leakage and tearing, said fastening elements being located exteriorly of the water proof fabric forming said body.

4. In a carrier for ice, a body formed from a single piece of waterproof fabric and being provided with a base portion, a boot receiving the base portion of said body and being provided with a bottom, side and end walls, the said side and end walls of the boot being provided with overlapped portions, inner and outer three-sided corner pieces at the corners of the boot and at the overlapped portions of the side and end walls of the boot, and rivets passing through the inner and outer corner pieces and the intervening portions and the said overlapped portions of the side and end walls of the boot and clamping such portions flatly between the corner pieces to protect the same against leakage and against tearing, said corner pieces and said rivets being located exteriorly of the waterproof fabric body.

5. In a carrier for ice, a body formed from a single piece of waterproof fabric and being provided with a base portion, a stiffening and reinforcing boot receiving the base portion and being provided with a bottom, side and end walls, the said side and end walls of the boot being provided with overlapped portions, and inner and outer rigid metal corner pieces at the corners of the boot and at the overlapped portions of the side and end walls of the boot, fastening elements passing through the inner and outer rigid metal corner pieces and the intervening and overlapped portions of the side and end walls of the boot and clamping such portions flatly between the rigid metal corner pieces to protect the same against leakage and against tearing, there being means securing the marginal portion of the boot to the adjacent portion of the body of the carrier.

6. In a carrier for the delivery of ice, a fabric body having a base portion defining a shallow container for the reception of ice and for drippings from ice, a boot receiving the base portion of the carrier and being provided with side and end walls and a bottom, and corner braces engaging the side and end walls and the bottom of said boot, and fastening elements securing the corner braces to the side and end walls and bottom of the boot and located entirely at the outer side of the base portion of the carrier.

7. In a carrier for ice, a body having a base portion defining a shallow container for ice and for the drippings from ice, a boot receiving the base portion of the carrier and provided with side and end walls having overlapped portions and with a bottom, and three-sided corner elements engaging the outer surfaces of the side and end walls and the bottom of the boot, and fastening elements passing through the side and end walls of the boot and the overlapped portions of said side and end walls and through the bottom wall of the boot and located entirely at the outer side of the base portion of the carrier.

8. In a carrier for ice, a body having a base portion defining a container for ice and for the

- 5 drippings from ice, a boot receiving the base portion of the body and being provided with corners, rigid metallic three-sided corner elements located between the corners of the boot and the base portion of said body and fastening elements extending through the corners of the boot and through the corner elements and located exteriorly of the base portion of the carrier.
9. In a boot for ice carriers, a body having a bottom, side and end walls, the side and end walls being provided with overlapped portions, corner pieces of three-sided formation located at the corners of the boot, and fastening elements passing through the corner pieces and the side and end walls and bottom and overlapped portions of the body of the boot.
10. In an ice carrier, a body formed from a single piece of waterproof fabric having side and end walls and a bottom, and three sided corner elements located at the corners of the carrier, and rivets passing through the corners of the body and through the corner elements and having broad terminal portions distributing the strain of the rivets to the adjacent portions of the waterproof fabric of the body of the carrier.
15. In a carrier for the delivery of ice, a body formed from a single piece of fabric having corner portions provided with inwardly extending folds defining side and end walls, said folds being permanently secured to the end walls, inner and outer corner elements of three-sided form located at the corners of the body, fastening elements passing through said corner elements, the side and end walls and through said folds and clamping the corner elements in pressure relation to the intervening fabric to protect the same against tearing and leakage.
20. In a carrier for ice, a fabric body formed from a single piece of material provided at spaced points with inwardly extending folds defining side and end walls and a bottom, and corner pieces engaging the side and end walls and the bottom, and fastening elements extending through the corner pieces and the side and end walls and the said folds and establishing a pressure relation between these parts and the corner pieces.
25. In a carrier for the delivery of ice, a waterproof fabric body having a base portion provided with side and end walls and a bottom wall, and inner and outer corner elements located at the juncture of the side and end walls and the bottom wall, and fastening elements passing through the inner and outer corner elements and the intervening portions of the side and end walls and the bottom wall of the base portion and clamping the corner elements in pressure contact with the intervening waterproof fabric of said body.
30. In a carrier for the delivery of ice, a body formed from a single piece of fabric having corner portions provided with inwardly extending folds defining side and end walls, said folds being permanently secured to the end walls, inner and outer corner elements of three-sided form located at the corners of the body, fastening elements passing through said corner elements, the side and end walls and through said folds and clamping the corner elements in pressure relation to the intervening fabric to protect the same against tearing and leakage.

WILBUR F. CRAWFORD. 30
